METHOD OF AND MACHINE FOR FINISH-
ING SEAMS

Dankmar Hallbauer, Beverly, Mass., assignor to
United Shoe Machinery Corporation, Paterson,
N. J., a corporation of New Jersey

Application August 14, 1935, Serial No. 36,176

13 Claims. (Cl. 69—7)

This invention relates to improvements in methods of and machines for operating upon shoe parts and is herein exemplified with reference to the finishing of seam ridges of seamed shoe parts.

It is customary, in the manufacture of shoes, to finish the seam known as the "back seam", which joins the parts of a quarter or lining made of two sections, as by pressing or rubbing it to reduce its height in order to avoid any ridge in the upper when it is lasted. The difficulty of reducing such a seam evenly and without its being pressed exclusively to one side or the other presents a problem with which the invention disclosed in an application for Letters Patent of the United States Serial No. 20,615, filed May 9, 1935, in the name of T. C. Rowen, is concerned and in the solution of which it has been found desirable to control the seam ridge laterally as its height is reduced.

It is a general object of this invention to extend and make further application of the above-mentioned principle in finishing seams, having in view the desirability of not only effectively and evenly reducing the seam ridge but also, at the same time, forming portions of the upper part contiguous to the seam into the shape they are to have in the finished shoe.

The invention in one aspect relates to a machine comprising means for supporting a seamed work-piece, said means having surfaces adapted to receive the seam ridge between them and arranged to prevent lateral displacement of the ridge by engagement with its sides, pressing means for holding the work-piece against said supporting means, means referred to later as a seam-ridge-reducing member cooperating with said pressing means to apply pressure to the ridge heightwise thereof in increasing amounts to successive portions of it, and means for operating the pressing means to impart a feed movement to the work-piece.

In the illustrated construction, lateral displacement of the seam ridge is prevented by providing a rotary work support having opposed radial surfaces between which the seam ridge is fed by a presser; and heightwise reduction of the ridge is effected as it passes between the presser and a rotary seam-ridge-reducing member the effective work-engaging surface of which progressively approaches that of the presser, considered in the direction of feed movement of the work, so that the seam ridge is crowded heightwise between the two last-named members. In order still further to reduce the size of the

seam ridge, the opposed radial surfaces of the work support, between which the seam ridge is fed, converge, considered in the direction of feed movement of the work, toward the locality in which the seam ridge is being pressed heightwise so that progressively increasing pressure is applied simultaneously to successive portions of the seam ridge both heightwise and widthwise.

In another aspect the invention relates to a method which may conveniently be practised by the use of a machine, as herein disclosed, comprising holding the seam ridge against lateral displacement, preferably by applying progressively increasing pressure to successive portions thereof, and reducing the seam ridge heightwise by applying progressively increasing pressure to said portions heightwise of the ridge.

These and other features of the machine, including certain details of construction and combinations of parts, will be described as embodied in an illustrative machine and pointed out in the appended claims.

Referring to the accompanying drawing, Fig. 1 is a view in perspective of an illustrative machine embodying the invention, parts of the operating tools being broken away and shown in section;

Fig. 2 is a fragmentary view, partly in section, of the operating tools;

Fig. 3 is a sectional view taken along the line III—III of Fig. 2; and

Fig. 4 is a fragmentary sectional view taken along the line IV—IV of Fig. 2, showing a work-piece being operated upon.

The machine in which the invention is illustrated as embodied is adapted to operate upon a seamed work-piece W having a seam ridge r extending from its normally concave surface as in the case of the ridge of the back seam in a shoe quarter. To insure against the seam ridge being disturbed after having been pressed, it has been found desirable to avoid bending the work-piece after its seam has been pressed, which practice results from pressing the seams of work-pieces in a flat or wrong-side-out condition and then forming them about a last. Accordingly, the work-piece W is supported, in the illustrated machine, in substantially its normal state of curvature by supports 10 and 12 which are shaped transversely in accordance with the horizontal curvature of the heel end of a shoe, as illustrated in Fig. 4, and having a peripheral curvature, as illustrated in Fig. 2, conforming substantially to the heightwise contour of the heel end of the shoe. The supports 10 and 12 have hubs 55

14 and 16 which are rotatably mounted in standards 18 and 20, respectively, arranged to extend upwardly from the base 22 of the machine frame. As illustrated in Figs. 3 and 4, the supports 10 and 12 are spaced to receive the seam ridge *r* the sides of which are engaged by radial surfaces 24, 24 of the supports and hence are prevented from being laterally displaced under the influence of pressure exerted heightwise of the seam ridge. Moreover, the axes of the hubs 14 and 16, about which the supports 10 and 12 rotate, are so angularly related in a plane indicated by the line III—III of Fig. 2 that the radial surfaces 24 of the supports 10 and 12 converge in the direction of feed movement of the work and hence form a bite widthwise of the seam ridge.

The work-piece *W* receives a feed movement from and is pressed against the supports 10 and 12 at portions adjacent to the seam ridge by a pressing member 26, the work-engaging surface of which is shaped in conformity to the transverse and peripheral contours of the supports 10 and 12. The pressing member 26 is mounted upon studs 28 arranged to slide in a rocker 30 upon studs 28 arranged to slide in a rocker 30 to a limited extent determined by nuts 32 at the upper ends of the studs 28. The pressing member 26 is caused yieldingly to press the work-piece *W* against the supports 10 and 12, after being moved into contact with the work-piece, as will be described later, by springs 34 which about the pressing member 26, encircle the studs 28 and are seated in recesses in the rocker 30. The rocker 30 is pivotally mounted on a stud 36 carried by a link 38, the latter being arranged to slide with respect to a block 40 and to swing about the center of a screw 42 which is threaded into the end of an overhanging arm 44 of the machine frame and which provides a support for the block 40. The link 38 receives a four-motion movement from a crank pin 46 extending from a drive shaft 48 journaled in the uppermost portion of the arm 44. The shaft 48 may be driven by any convenient means such as a pulley 50 and belt 52 connecting the pulley 50 with a suitable 45 source of power.

The pivotal connection between the link 38 and the rocker 30 provided by the stud 36 permits the pressing member 26, after being moved into contact with the work-piece *W*, to seat itself and 50 to remain seated on the work-piece throughout the period when the work-piece is pressed notwithstanding the swinging movement of the link 38. That is, as the link 38 moves downwardly 55 viewed in Figs. 1 and 2, first presses the work-piece against the supports 10 and 12. Thereafter, the pressing member 26 is swung about its right-hand end, Figs. 1 and 2, into complete contact with the work-piece, this movement being 60 permitted by the pivotal connection between the rocker 30 and the link 38 on the stud 36. Additional downward movement of the link 38 causes 65 the relative movement between the rocker 30 and the pressing member 26, compression of the springs 34, and hence the application of yielding pressure to the work-piece. Components of the movement of the link 38 extending peripherally of the supports 10 and 12 from left to right (Figs. 1 and 70 2) cause the pressing member 26 to impart a feed movement to the work which is thus presented step by step to the bite between the surfaces 24 of the supports 10 and 12 resulting from their convergence. Finally, as the pressing member 26 is raised from the work a spring 54, received 75 between pins 56 on the link 38 and clamped by

a screw 58 in a slot in the rocker 30, gradually moves the rocker 30 and the pressing member 26 into a central position generally normal to the longitudinal axis of the link 38.

While the seam ridge *r* is thus controlled and 5 pressed widthwise between the surfaces 24, 24, it is also reduced heightwise until it is substantially continuous with the side of the work-piece from which it extends by the action of a reducing member 60 carried by a rotating shaft 62, the latter 10 being rotatably mounted in bearings one of which is formed in a standard 63 formed integral with the base 22 and the other of which (not shown) is in the lower portion of the arm 44. The shaft 62 is driven from the drive shaft 48 by connections comprising pulleys 64 and 66 over which runs a belt 68. The reducing member 60 is housed within the supports 10 and 12, as illustrated in Figs. 1 and 3, and has a disk-like central portion 70 which is received between the surfaces 20 24 of the supports 10 and 12 and the periphery of which converges toward and becomes substantially continuous with the peripheral surfaces of the supports 10 and 12, thereby forming a bite 25 with the work-engaging surface of the pressing member 26 heightwise of the seam ridge when the pressing member holds the work-piece against the supports 10 and 12.

The reducing member 60 is rotated at a speed 30 such that its peripheral velocity is substantially greater than the feed movement of the work-piece, thereby to effect a burnishing or rubbing action on the seam ridge, it having been found that this method of reducing a seam ridge minimizes the danger of breaking the stitching and 35 insures a permanently pressed seam. The property of heat to shrink and set leather also is used to advantage in the illustrated machine owing to the provision of a heated guide 72 having an electric heating unit 74 and mounted in heat-ex- 40 change relation to the supports 10 and 12. Thus, the work-piece *W*, in being pressed into conformity to the shape of the supports 10 and 12 in their heated condition, receives a partial set 45 while in this curved state which it tends to retain notwithstanding the flexing to which it is subjected in handling incidental to forming the upper about a last. The reducing member 60 also is heated by radiation from the guide 72 and by virtue of its proximity to the heated supports 10 50 and 12. Substantial additional heating of the reducing member 60 itself is obtained by its frictional engagement with the seam ridge further to insure adequate finishing of the seam ridge itself. The guide 72 may be fixed to the base 22 55 by any convenient means, it being desirable to interpose therebetween a layer of heat insulation 76 to prevent undue loss of heat to the base 22. The upper surface of the guide 72 is grooved at 78 to receive the seam ridge of the work-piece and 60 is aligned with the reducing member 60 and the surfaces 24, 24 of the supports 10 and 12 to facilitate the proper register of the seam ridge with respect to these parts of the machine. The upper surface of the guide 72 is also transversely rounded 65 so as initially to shape the work-piece *W* transversely of the seam ridge substantially into the form in which it is pressed by the pressing member 26.

While the operation of the machine will be 70 readily understood from the foregoing, it will now be summarized briefly. The member 74 having been heated to the desired temperature, the work-piece *W* is placed thereon, the seam ridge *r* being received within the groove 78. The work-piece 75

is then moved into engagement with the supports 10, 12 beneath the pressing member 26, the latter being continuously moved in a generally elliptical path. As the pressing member 26 approaches the supports 10, 12, certain components of its movement directed peripherally of the supports 10 and 12 cause a feed movement to be imparted to the work-piece in the direction of the arrow, as illustrated in Fig. 1, from the front toward the rear of the machine. Owing to the bite heightwise of the seam ridge *r* formed by the reducing member 60 and the pressing member 26, pressure is imparted in increasing amounts to successive portions of the seam ridge as it passes underneath the pressing member 26; and simultaneously the seam ridge, in being presented to the bite widthwise of the ridge formed by the surfaces 24, 24 is prevented from being laterally displaced toward one side or the other and is uniformly reduced across its entire width by the reducing member 60. Thus, the seam ridge *r* is reduced heightwise until it is substantially continuous with the side of the work-piece from which it extends, insurance that the seam ridge will thus be treated being afforded by the action of the surfaces 24, 24 of the supports 10, 12 which prevent the ridge at any time from escaping the pressing action of the pressing member 26 and the reducing member 60. The effective reduction of the ridge is also furthered by the intermittent pressing action of the pressing member 26 which, in being moved into and out of engagement with the work-piece *W* rapidly, tends to beat the seam ridge against the reducing member 60 but without rupturing the stitching. The machine is thus arranged not only to press the seam ridge in the manner described above, but also to form portions of the work-piece *W* adjacent to the seam substantially into the curved shape which they are to have in the finished shoe by the combined action of pressure and heat imparted to the work-piece when subjected to the action of the pressing member 26 and the supports 10 and 12.

Having thus described my invention, what I claim as new and desire to secure by Letters Patent of the United States is:

1. In a seam-finishing machine, work-supporting members spaced to receive a seam ridge therebetween and arranged to prevent lateral displacement of the seam ridge, a pressing member for holding portions of the work-piece adjacent to the seam ridge against said supporting members, a seam-ridge-reducing member cooperating with said pressing member to apply pressure to the seam ridge heightwise thereof to successive portions in progressively increasing amounts, and means for operating said pressing member to impart a feed movement to the work-piece.
2. In a seam-finishing machine; means for supporting a seamed work-piece, said means having surfaces adapted to receive a seam ridge therebetween and arranged to prevent lateral displacement of the ridge by engagement with its sides, pressing means for holding the work-piece against said supporting means, means cooperating with said pressing means to apply pressure to the ridge heightwise thereof and in increasing amounts to successive portions thereof, and means for operating said pressing means to impart a feed movement to the work-piece.
3. In a seam-finishing machine, means for supporting a seamed work-piece, said means having spaced surfaces adapted to receive the seam ridge therebetween and to prevent lateral displacement

of the ridge, a pressing member mounted and arranged to hold portions of the work-piece adjacent to the seam ridge against said means, means cooperating with said pressing member to form a bite heightwise of the seam ridge, and means for operating said pressing member to impart a feed movement to the work-piece toward said bite.

4. In a seam-finishing machine, means for supporting a seamed work-piece, said means having guiding surfaces spaced to receive the same ridge therebetween and arranged to engage the sides of the seam ridge to prevent its lateral displacement, pressing means for holding the work-piece against said supporting means, means having a seam-ridge-engaging surface converging with the work-engaging surface of said first-mentioned means, and means for operating said pressing means to impart a feed movement to the work-piece.

5. In a seam-finishing machine, means for supporting a seamed work-piece, said means having surfaces spaced to receive a seam ridge therebetween and arranged to prevent lateral displacement of the seam ridge, pressing means for holding the work-piece against said supporting means, a rotating seam-ridge-reducing member the periphery of which converges toward said pressing means, and means for operating said pressing means while in engagement with the work-piece to impart a feed movement thereto.

6. In a seam-finishing machine, rotatable supports spaced to receive the ridge of a seamed work-piece therebetween and having radially extending surfaces arranged to prevent lateral displacement of the seam ridge, pressing means constructed and arranged to hold the work-piece against said supports and cooperating therewith to impart a feed movement to the work-piece, and means for reducing the height of the seam ridge mounted for movement so that its ridge-engaging surface progressively approaches the pressing means whereby the height of the seam ridge is progressively reduced.

7. In a seam-finishing machine, rolls spaced to receive the ridge of a seamed work-piece therebetween and mounted to rotate about angularly related axes, a pressing member, a rotating member mounted eccentrically with respect to said rolls and cooperating with said pressing member to form a bite heightwise of the seam, and means for operating said pressing member to hold the work-piece against the rolls and impart a feed movement to the work-piece.

8. In a seam-finishing machine, means for supporting a seamed work-piece, said means having convergent surfaces spaced to receive a seam ridge therebetween and adapted to prevent lateral displacement of the seam ridge, a pressing member for holding the work-piece against said means, a seam-ridge-reducing member cooperating with said pressing member to form a bite heightwise of the seam, and means for operating said pressing member to impart a feed movement to the work-piece toward said bite.

9. In a seam-finishing machine, means for supporting a seamed work-piece, said means having peripheral surfaces arranged to engage the work at each side of the seam and radial surfaces arranged to prevent lateral displacement of the seam ridge by engagement with the sides thereof, a pressing member for holding the work-piece against the peripheral surfaces of said supporting means, a seam-ridge-reducing member the surface of which converges toward the said

- peripheral surfaces of said supporting means thereby to form a bite with said pressing member, and means for operating said pressing member to impart a feed movement to the work-piece.
10. In a seam-finishing machine, work-supporting members spaced to receive a seam ridge therebetween and mounted for movement in converging directions thereby to press the seam ridge widthwise, a pressing member constructed and arranged to hold portions of the work-piece at each side of the seam ridge against said supporting members, and a seam-ridge-reducing member mounted for movement in a direction converging with the work-engaging surfaces of said supporting members, said pressing member coöperating with said work-supporting members to impart a feed movement to the work-piece.
11. In a seam-finishing machine, spaced work-supporting members mounted at an angle to each other so as to form a bite widthwise of the ridge of a seam received therebetween, a pressing member arranged to hold portions of the
- work-piece at each side of the seam ridge against the supporting members, and a seam-ridge-reducing member coöperating with said pressing member to form a bite heightwise of the ridge, said pressing member being operable to move 5 the work-piece toward said bites simultaneously.
12. That improvement in methods of finishing the seam ridge of a seamed work-piece which consists in holding the sides of the ridge against lateral displacement, and reducing the ridge 10 heightwise by applying progressively increasing pressure heightwise of the ridge to successive laterally controlled portions of the ridge.
13. That improvement in methods of finishing the seam ridge of a seamed work-piece which 15 consists in applying progressively increasing pressure laterally of the seam ridge to successive portions thereof, and, simultaneously with the application of lateral pressure, applying progressively increasing pressure heightwise of the 20 seam ridge to the same successive portions.
